J. D. RYAN

GENERATOR AND BATTERY PROTECTIVE MEANS

Filed March 2, 1922

UNITED STATES PATENT OFFICE.

JERRY D. RYAN, OF BRONSON, MICHIGAN.

GENERATOR AND BATTERY PROTECTIVE MEANS.

Application filed March 2, 1922. Serial No. 540,474.

To all whom it may concern:

Be it known that I, JERRY D. RYAN, a citizen of the United States, residing at Bronson, in the county of Branch and State of Michigan, have invented new and useful Improvements in Generator and Battery Protective Means, of which the following is a specification.

The object of my said invention is the provision of simple and reliable means for precluding the burning out of electric generators and preventing the discharging of storage batteries such as used in the ignition systems of automobiles.

To the attainment of the foregoing, the invention consists in the improvement as hereinafter described and definitely claimed.

In the accompanying drawings, forming part of this specification:—

Figure 1 is an end elevation of a generator and my improvement.

Figures 2 and 3 are enlarged vertical sections taken in the planes indicated by the lines 2—2 and 3—3, respectively, of Figure 1, and

Figure 4 is a diagrammatic view showing the normal arrangement of the improvement.

Similar numerals of reference designate corresponding parts in all of the views of the drawings.

The generator 1 is grounded at 2 and may be of the ordinary well known construction or of any other construction compatible with the purpose of my invention.

The storage battery 3 may be of any approved type, and is grounded at 4.

At 5, Figure 4, is a terminal grounded at 6, and at 7 is the usual cut-out appurtenant to the generator 1.

In the present and preferred embodiment of my invention the terminal 5 is formed by a grounded casing connected at 8, to the generator casing and designated by 5 in the figures.

According to my invention a fuse 8 is interposed in the electrical connection between the cut-out 7 and the battery 3, the said fuse 8 being arranged transversely in the casing 5 and between terminals 9 insulated from the walls of the casing as designated by 10 in Figures 2 and 3.

Connected to one wall of the casing 5 but insulated therefrom as indicated by 11 in Figures 2 and 3 is a resilient grounding device 12 on which is a contact 13. The said

grounding device is arranged within the casing 5 as is also a dielectric hook 14, pivotally connected at 15 to the device 12 and normally resting in engagement with the fuse 8. In said engagement which obtains so long as the fuse 8 is intact, the grounding device 12, which is electrically connected at 16 with the generator 1 is held out of electrical connection with the casing 5. When, however, the points of the cut-out 7 stick or the generator overcharges, the fuse 8 will be consumed and will automatically release the hook 14 and permit the device 12 to snap into contact with the casing 5, with the result that the generator will be grounded as designated by 6 in Figure 4 so that the automobile can be operated without injury to the generator 1.

It will also be manifest that when the battery 3 is removed from the automobile, the hook 14 may be manually disengaged from the fuse 8 to ground the generator through the device 12 and the casing 5, whereupon the car may be operated with ignition furnished from a magneto without injury to the generator 1.

I have entered into a detailed description of the construction and relative arrangement of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my invention as defined in my appended claims.

Having described my invention, what I claim and desire to secure by Letters-Patent, is:—

1. In protective means for the purpose set forth, the combination of a generator, means to electrically connect the generator and a storage battery and formed in part by a fuse, a grounded terminal, and means electrically connected with the generator and insulated from said fuse and normally held by the fuse away from said grounded terminal and tending when released to contact with said terminal and thereby ground the generator.

2. In protective means for the purpose set forth, the combination of a generator,

means to electrically connect the generator and a storage battery and formed in part by a fuse, a grounded terminal, and means electrically connected with the generator and 5 insulated from said fuse and normally held by the fuse away from said grounded terminal and tending when released to contact with said terminal and thereby ground the generator; the said grounded terminal being 10 formed by a casing containing and insulated from the fuse and the last-named means.

3. In protective means for the purpose set forth, the combination of a generator, means to electrically connect the generator and a 15 storage battery and formed in part by a fuse, a grounded terminal, and means electrically connected with the generator and insulated from said fuse and normally held by the fuse away from said grounded terminal and tending 20 when released to contact with said terminal and thereby ground the generator; the said grounded terminal being formed by a casing containing and insulated from the fuse and the last-named means, and the said 25 last-named means being in the form of spring strip on which is a pivoted insulated hook normally engaging and held by the fuse.

4. In a starting and lighting system for automotive vehicles including a generator, a battery and an automatic cut out disposed between the battery and generator, of a protecting device for the system when the automatic cut out fails to function including a fuse wire interposed in the circuit 35 adapted to burn out when the battery discharges through the generator and cut out, and a switch for grounding the generator normally held in open position by said fuse 40 wire.

5. In a starting and lighting system for automotive vehicles including a battery, a generator, and an automatic cut out, of a protecting device for the system when the 45 cut out fails to function including a fuse wire interposed between the battery, generator and cut out adapted to burn out when the battery discharges through the cut out and generator, and a switch for grounding 50 the generator when the fuse wire burns out including a movable contact and a stationary contact, the movable contact being normally held out of engagement with the stationary contact by said fuse wire.

In testimony whereof, I affix my signature.
JERRY D. RYAN.
